W. G. WOLFE,
AUTOCLAMPING LAMP GUARD.
APPLICATION FILED JULY 12, 1920.
1,410,150.

Patented Mar. 21, 1922.

Inventor:

Waldo G. Wolfe

UNITED STATES PATENT OFFICE.

WALTER G. WOLFE, OF SAN PEDRO, CALIFORNIA.

AUTOCLAMPING LAMP GUARD.

1,410,150.

Specification of Letters Patent. Patented Mar. 21, 1922.

Application filed July 12, 1920. Serial No. 395,773.

To all whom it may concern:

Be it known that I, WALTER G. WOLFE, a citizen of the United States, residing at San Pedro, in the county of Los Angeles and State of California, have invented a new and useful Autoclamping Lamp Guard, of which the following is the specification.

My invention relates to combined guard and reflector or shade for electric lamps.

10 An important object of my invention is to provide a combined guard and shade or reflector for electric lamps having improved automatic clamping means to permit of the ready attachment to, or removal from the 15 socket commonly employed with electric lamps.

A further object of the invention is to provide a device of the class described which is simple, neat in appearance and cheap to 20 manufacture.

In the accompanying drawing in which like reference characters indicate like parts throughout the several views,

25 Fig. 1, is a front elevation of my device showing the parts in assembled relation.

Fig. 2, is a side elevation of Fig. 1,

Fig. 3, is a front elevation of my shade or reflector with guard or gate removed.

30 Referring to the drawing in detail, 1, indicates a shade or reflector with the sides, 3, bent at angles terminating at its rear or socket end, in a constructed curved resilient split neck portion, 2.

35 The shade or reflector is further provided with perforations, 15.

The neck, 2, of the shade or reflector, is bent at its open ends to form wings, 4, which are provided at diametrically opposite points with bores or holes, A, through which bores 40 or holes, a rod or bolt, 5, is inserted, said rod acting, as a pivot on which the semi-bulbous shaped guard or gate portion, E, is adapted to swing into opened or closed position, and also acts as a means whereby 45 the device is held together in its entirety.

The neck, 2, is further provided with wedge shaped portions, D, D, placed adjacent and in close proximity to the holes, A, the purpose of which will be explained later.

50 The guard or swinging gate, E, is bent into a shape, more or less resembling a horse shoe, having the forward portion flattened and the side frames, 7, 8, longitudinally

curved, and horizontally curved wires, 14, spaced equidistant apart.

55 The longitudinally curved side frames, 7, 8, converge toward the center terminating in enlarged rear end portions, C, C,—said portions, C, C, being provided with bores or holes, 12, 12, and said bores or holes being 60 out of line with the radial center of the said end portions, C, C.

The rear end portions, C, C, being enlarged and mounted eccentrically, will always present a bearing surface to wedge 65 shaped portions, D, D, and as the gate is swung to closed or operative position, said ends, C, C, acting on the wedge shaped portions, D, D, will tend to draw the neck, 2, into frictional engagement with the lamp 70 socket.

Upon inward movement of the swinging guard or gate, E, to locked position the enlarged and eccentrically mounted ends, C, C, of the frame members, 7, 8, slide on the 75 wedge shaped faces of the portions, D, D, traveling toward the higher part of said wedge shaped portions, D, D.

This tends to contract the neck, 2, and bring it into frictional engagement with the 80 lamp socket, which engagement locks my device into secure position.

Upon outward movement of the guard or gate, E, to open position the ends, C, C, ride toward the smaller parts of wedge shaped 85 portions, D, D, thus allowing the neck to spring open, and disengage itself from the lamp socket, which will permit of the ready removal of the lamp or the device as a whole.

90 The forward end of the shade or reflector, 1, extends a short distance beyond the upturned sides, 3, and is turned over upon itself, or beaded, as at, 13, thus providing a shoulder over which the forward and flattened portion of the hinged guard or gate, E, is snapped when the device is in use.

100 In the practice and use of my invention the guard or gate, E, is moved outwardly on its pivot to permit the socket to be inserted into the neck portion, 2,—an electric light bulb is then screwed, or otherwise fixed into the socket.

105 The swinging guard or gate, E, is now swung into closed position the eccentrically mounted ends, C, C, pressing against the

faces of the wedge shaped portions, D, D, which causes the neck, 2, to contract and frictionally engage the lamp socket.

This provides a quick and secure means 5 of holding my device in operative position.

When it is desired to remove a globe the hinged guard or gate, E, is merely released from the retaining bead, 13, and pulled outwardly—this will permit of the taking out 10 and the ready insertion of a new globe or the removal of the device as a whole.

In using the device in connection with drop cord lights, extensions or portable cords employed in shops, garages and other 15 places, the shade or reflector, 1, serves to protect the eyes of the user, and also directs the light to the work—and as the shade or reflector, 1, is flat on its sides, it can be rested upon a floor, table, bench or any surface 20 and will not roll around or turn over—thus doing away with this particular annoyance, which is common in devices of this character not possessing this feature.

The hinged guard or gate, E, together 25 with the shade or reflector, 1, serves to protect the globe from accidental fracture.

The perforations, 15, provide for ventilation.

Having thus described my invention, 30 what I claim is—

1. The combination with a reflector, having wedging surfaces, of means pivoted to said reflector and forming an actuating engagement with said wedging surfaces, 35 for causing clamping contraction of said reflector.

2. The combination with a reflector of a guard pivoted to the same, and means actuated by said guard for securing the device in position.

3. The combination with a reflector having a split neck, of wedging means upon the ends of said neck, a guard adapted to engage said wedging means so as to restrict said neck and secure the reflector in position. 45

4. The combination with a reflector having a split neck, of wedging members upon said neck, and means eccentrically pivoted to said reflector and adapted to engage said wedging members so as to restrict said neck 50 and secure the reflector in position.

5. The combination with a reflector having a split neck, of wedging members upon said neck, and a guard for said reflector having arms eccentrically pivoted to the reflector at said neck, said arms being adapted to engage said wedging members so as to restrict said neck and secure the reflector in position. 55

6. The combination with a reflector having a flattened surface and a split neck at one end, of a guard for said reflector pivoted to the same at said neck, said guard and neck co-operating to restrict the neck by the swinging movement of the guard. 60

In testimony whereof I have signed my name to this specification in the presence of two subscribing witnesses.

WALTER G. WOLFE.
